UNITED STATES PATENT OFFICE

2,481,920

MAGNETIC GOVERNOR

Charles L. Fitz, Albany, Calif., assignor of one-half to Fred Dobbs and one-half to Charles L. Fitz, copartners, Three Lakes, Wis.

Original application August 15, 1941, Serial No. 406,942. Divided and this application July 12, 1945, Serial No. 604,626

11 Claims. (Cl. 188—104)

1

This invention relates to a magnetic governor. The present application is a division of my application Ser. No. 406,942, filed August 15, 1941, and issued October 2, 1945, for a Camera, as Patent No. 2,385,804, in which patent the governor is shown as a means of regulating the rate of movement of a camera shutter.

It is a primary object of the invention to provide a novel and improved governor preferably using a permanent magnet and adjustable as to the governing effect of such magnet with reference to a rotatable or oscillatable armature. My purposes will appear more fully in connection with the following disclosure of the invention.

In the drawings:

Fig. 1 is a plan view of apparatus embodying the invention.

Fig. 2 is a side elevation of the apparatus shown in Fig. 1, a cover plate and portions of a supporting frame being shown in section.

Fig. 3 is a detail view fragmentarily illustrating in plan a portion of the apparatus shown in Fig. 1.

While the mechanism governed in the accompanying disclosure of the invention happens to be a portion of the shutter operating mechanism shown in the parent application above identified, it will, of course, be understood that the invention is of more general application. Merely by way of exemplification, the mechanism governed may comprise a gear 4 driven by a spring motor comprising the shell 5 and the torsion spring 6, the spring being connected, for winding, to the gear 7.

The gear 4 driven by the spring motor is regulated as to its rate of rotation by a rotor which as shown, comprises a pinion 8 meshing with the gear and an armature which may constitute a segment 9, as shown in Figs. 1 and 2 or a complete annulus 10, as shown in Fig. 3. The rotors made up of disks or armatures 9 or 10 and gear 8 preferably comprise ferrous or other magnetic material and are mounted to turn unitarily on the headed stud 11. Each of the armatures 9, 10 alternatively usable upon the gear 8 is provided with polar extensions 12 which preferably project axially as shown. The only difference between the armature 9 and the armature 10 consists in the fact that armature 10 is provided with a complete annular series of the polar extensions 12, whereas armature 9 has the polar extensions about only a portion of its periphery. In the case of the armature 9, the magnetic governing action hereinafter to be described will be effective on the armature only for the arcuate extent of its

2

series of polar extensions, whereas, in the case of the armature 10, the arcuate extent of the series of polar extensions comprises a complete circle so that the magnetic governing action will be effective continuously throughout armature rotation.

The frame member 13 is preferably likewise of ferrous or other magnetic material, as are the post 14 mounted thereon and the spring 15 supported by such post. The spring provides upward bias, as well as a fulcrum, for the bar magnet 16, the end of which is provided with a plurality of poles (preferably three in number) 17, 18, 19 which are formed concentric with the axis upon which the rotor 8, 9 revolves. Thus the polar extensions 12 of the armature rotate in immediate proximity to the poles 17, 18, 19 of the bar magnet 16. Additional upward bias for the bar magnet may be provided if desired by a supplementary spring 20 which preferably acts on the bar magnet substantially at its center. Opposed to spring 20 in its operation on the bar magnet is the adjusting screw 21 threaded into a suitable boss in the cover plate 22 and adjustable against the bias of magnet 16 to force the magnet from the fully retracted position in which it is illustrated in full lines in Fig. 2 to the fully advanced horizontal position in which it is illustrated in broken lines in Fig. 2.

30 In the horizontal position of the magnet, it develops its maximum braking effect on the armature 9. In the course of armature rotation, the several poles 12 of the armature are rotated past the several poles 17, 18, 19 of the bar magnet 16 thereby developing currents in the armature and magnet which increase in intensity in proportion to the speed of rotation of the armature 9, 10. The intensity of such currents is also a function of the proximity of the magnet to the plane in which the armature rotates. The resistance offered to armature rotation is, in turn, proportioned to the intensity of the currents magnetically developed by the interaction of the poles 12 with the poles 17, 18, 19. Consequently, a retarding or braking effect is exerted which tends to slow the rotation of the armature and this effect may be regulated by means of the screw 21 and the opposing bias of the magnet whereby the magnet may be adjusted for any desired range 40 of pivotal movement respecting the plane in which the armature rotates.

An additional braking action may be secured by using flexible brake shoes 23 of magnetizable material acting between the frame member 13 and the rotor which comprises gear 8 and armature 9,

As shown, these shoes are riveted to the frame member 13 and have bearing portions in light friction contact with the under surface of gear 8. The particular arrangement is purely by way of exemplification. When the magnet 16 is in close proximity to the rotor, some of its magnetism is communicated through the rotor to attract the magnetizable, flexible shoes 23 and thereby to increase their frictional bearing pressure on the rotor and, consequently, their drag or braking effect. Where the frame member 13, the support 14 and the spring 15 are all made of magnetizable material, a substantially closed magnetic circuit is established whereby the attraction between the shoes 23 and the parts frictionally engaged thereby is enhanced. The frictional braking pressure of the shoes 23, like the purely magnetic resistance developed in the armatures 9 or 10, depends for its intensity upon the position of the magnet 16. It will be relatively slight when the magnet is in the elevated position in which it is shown in full lines, and will be relatively strong when the magnet is in the horizontal position in which it is shown in broken lines.

While the members 9 or 10, with pinion 8, have been described as a rotor for the purposes of the present disclosure, it will be apparent that any one of these members may constitute the rotor in lieu of this composite rotor as illustrated. It will also be possible that a variety of changes are contemplated to be made within the scope of this disclosure and the appended claims.

I claim:

1. A rotor comprising a rotatably mounted armature having polar extensions in arcuate series, in combination with a bar magnet having terminal polar projections complementary to those of the armature, and means supporting the bar magnet for relative adjustment of its polar projections to and from the plane of rotation of said armature and to and from proximity to the polar extensions of said armature.

2. In a governor, the combination with a rotor having polar projections in arcuate series, of a resiliently supported non-rotatable magnet having terminal polar projections complementary to those of the rotor and arranged for magnetic interaction therewith to develop a resistance to rotor rotation, means for yieldingly supporting the magnet for movement of its polar projections toward and away from the rotor, said magnet being biased for normal movement of its poles away from the rotor, and means for adjusting said magnet in opposition to its said bias, whereby to predetermine the normal spacing between its poles and those of the rotor to vary its initial responsiveness in the magnetic field of the rotor.

3. In a magnetic governor, the combination with a rotor and a magnet mounted for relative movement to and from each other, of a support in proximity to the rotor, and a magnetically responsive shoe acting between the rotor and support and having a friction brake portion of variable effect in accordance with the magnetic energy communicated to the shoe through said rotor from said magnet.

4. The combination with a support member and a rotor member, of a flexible magnetic shoe connected with one of said members and in frictional bearing engagement with the other, said last mentioned member and shoe comprising magnetically responsive material, and a magnet provided with an adjustable support on which said magnet is movable to and from said last mentioned member whereby to communicate to

said member and said shoe a variable magnetic attraction toward said member depending on the relative position of the magnet respecting said member.

5. In a magnetic governor, the combination with a rotor member, a support member, and a flexibly yieldable shoe mounted on one of said members and in frictional bearing engagement with the other, said shoe and members all comprising magnetically responsive material, of a magnet having a magnetically responsive connection with said support member and having polar portions in proximity to said rotor member whereby said magnet and its said connection and said support member and shoe and rotor member constitute a magnetic circuit substantially closed save for the gap between the polar portions of the magnet and said rotor member, said magnet being adjustable upon its said connections whereby to vary said gap.

6. The combination with a magnet, a rotor member and a support member, of a shoe flexibly mounted on one of said members and in frictional engagement with the other and comprising magnetically responsive material, and means supporting said magnet for adjustment respecting at least one of said members, said means and magnet and members and shoe comprising a magnetic circuit in which the adjustment of the magnet affords a variable gap for regulating the pressure contact of the shoe on the member frictionally engaged thereby.

7. The combination with a support, of a rotor provided with axial polar projections in arcuate marginal series, at least one flexible brake shoe mounted on the support and flexibly engaging the rotor, a bar magnet having longitudinally projecting polar portions complementary to the axial polar extensions of the rotor, means mounting the end of the magnet remote from said polar portions for pivotal movement respecting the support whereby said magnet polar portions are movable to and from the plane of rotor rotation, and means for regulating the angular positioning of the magnet, said magnet and its mounting and the said support and rotor and shoe comprising magnetically responsive material in a circuit substantially closed save as determined by the angular position of the magnet and the consequent gap between its polar portions and polar extensions of the rotor.

8. In a governor, the combination with a magnet member and an armature member mounted for relative rotation and having mutually complementary poles, the poles of one of said members being in arcuate series, said last mentioned member being rotatable and the arcuate extent of the poles of said series being less than 360 degrees, together with a supporting member adjacent the rotatable member, a brake shoe operative between the rotatable member and the supporting member and connected to one thereof, said brake shoe being of magnetizable material whereby its braking effect will vary according to the continuity of the arcuate series of polar extensions on the rotatable member and the proximity of such polar extensions to the polar extensions on the first mentioned member.

9. In a governor, the combination with a magnetizable frame member, of a rotatable armature mounted thereon and having polar projections in arcuate series, a spring motor having gear connection with said armature, a non-rotatable magnetic brake resiliently mounted on said frame member and having terminal polar projections

complementary to those of the armature, resilient means for normally retracting said brake to reduce the intensity of the magnetic field between it and the armature, and adjustable means for variably limiting the degree of brake retraction, whereby said brake is given a predetermined range of movement in correspondence with the varying intensity of the magnetic field due to variations in the speed of the armature.

10. The combination with a magnetic rotor provided with poles and with a rotative mounting, of a non-rotative magnetic brake member provided with a support remote from said rotor and having a pivotal connection with said support, said member being provided with a free end portion adjacent the rotor having poles complementary to those of the rotor and movable about said pivotal connection to and from the plane of rotation of the rotor, together with means comprising an adjusting screw bearing on said member for adjustably determining the position of said member respecting said rotor, whereby to vary the magnetic braking interaction between the poles of said member and those of said rotor.

11. The combination with a magnetic rotor

5 provided with poles and with a mounting for rotation, of a support remote therefrom, a flexible spring mounted on the support, a magnetic brake member carried by the spring and supported thereby from said support, said member being provided at its free end with poles complementary to those of the rotor and disposed in proximity thereto and relatively removable upon said spring pivotally to and from the plane of rotation of the rotor poles, and means comprising an opposing spring and screw bearing on said member for adjustably determining the relative positions of the poles of said member respecting those of said rotor.
